UNITED STATES PATENT OFFICE.

EDWARD FRANK DUDLEY, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

BED-MOTION.

1,284,183.

Specification of Letters Patent.

Patented Nov. 5, 1918.

Application filed September 2, 1916. Serial No. 118,189.

To all whom it may concern:

Be it known that I, EDWARD F. DUDLEY, a citizen of the United States, residing at Oak Park, in the county of Cook and State of Illinois, have invented certain new and useful Improvements in Bed-Motions, of which the following is a specification.

The invention relates to mechanism for converting rotary motion into to and fro rectilinear or reciprocating motion. It has more especial reference to means of this kind for utilizing rotary motion for reciprocating the bed of a printing press or like machine.

15 In devices for this purpose the bed is driven throughout the greater part of its stroke at a constant rate of speed by suitable constant speed mechanism, and is slowed down, stopped, and started on its return stroke at each end of its travel by reversing mechanism embodying devices giving the bed a rate of speed gradually decreasing from the maximum speed to a point of rest and increasing from such point of rest until 20 the maximum speed is again attained.

It has been usual in mechanism of this character to employ such shifting devices comprising parts which reciprocate with the bed and at the time of reversal are moving in the same direction as the bed, thus disadvantageously adding their momentum to that of the bed, the total of which must be overcome to bring the latter to a stop for reversal. It has also been customary to 35 employ gears axially shifted to bring them into engagement alternately with oppositely rotating gears in order to reverse the direction of bed travel. Likewise, an objectionable feature found in bed shifting mechanism is the disposition of the operating parts at such distance below the plane of the bed as to preclude the employment of sufficiently massive and most efficiently distributed supporting pillars.

40 By the present invention the bed reversing devices reciprocate, at the moment of reversal, in a direction counter to the direction of movement of the bed prior to reversal, thus aiding in neutralizing the jars and strains incident to reversal and due to the momentum of the bed and counteracting the tendency of the press to slide on the floor, thus minimizing the strains on the press frame. These bed shifting devices are, 45 moreover, on the same side of the center of

gravity of the press as the bed itself thus avoiding any torsional strain on the press in a vertical plane tending to tip the press upon reversal. Furthermore shiftable gears are dispensed with and the power is transmitted by the gears in a constant manner without shock. Other advantageous characteristics of the invention from the standpoint of simplicity, compactness, efficiency and dependability for the purposes intended will 60 be apparent to those skilled in the art from a further consideration of the constructional features of the invention as set forth, by way of example, in the following detailed description of one embodiment thereof as 65 illustrated in the accompanying drawings, wherein:

Figure 1 is a view illustrating in side elevation a printing press embodying the invention;

Fig. 2 is a longitudinal vertical section looking in the opposite direction from Fig. 1;

Fig. 3 is a central transverse vertical section taken on the line 3—3 of Fig. 1;

Fig. 4 is a partial transverse vertical section on the line 4—4 of Fig. 1;

Fig. 5 is a fragmentary section on an enlarged scale taken on the line 5—5 of Fig. 3;

Fig. 6 is a similar section taken on the line 6—6 of Fig. 3;

Fig. 7 is a view similar to Fig. 3 but illustrating a modified form of driving gear train;

Fig. 8 is a side elevation of Fig. 7; and

Fig. 9 is a section on the line 9—9 of Fig. 7.

In these drawings the frame of the press is indicated generally at 11, the printing cylinder at 12 suitably journaled in the frame, details not shown, and the central supporting pillar at 13. These old and well known elements of press construction are shown in a diagrammatic manner only, 95 being of any well known type of construction and arrangement.

Power from any suitable source is transmitted by the power shaft 14, the gear 15, the gear 16 and the gear 17 for rotating the 105 impression cylinder 12 at a constant speed in a given direction. The shaft 18 of the gear 16 carries in addition to the gear 16 a gear 19, a gear 20, and a crank arm 21. The gear 19 on the shaft 18 is in mesh with 110

a large gear 22 which throughout substantially one-third of its periphery is double-faced, that is to say, the teeth 22^a are substantially twice the width of the teeth 22^b, the gear 19 being of a width corresponding to the width of the teeth 22^b, the extra width of the teeth 22^a extending to one side of the gear 19.

The gear 20 on the shaft 18 which may be called a transmission shaft, is in mesh with a slightly smaller gear 23 which in turn meshes with a larger gear 24 mounted upon the same shaft 25 with the gear 22 previously referred to but rotating loosely thereon. The gear 24 is concentric with the gear 22 but of slightly less diameter and has integral therewith or fixed thereon by means of the bolts 26, 26 or in other suitable manner, a sector 27 having a toothed periphery 28 in a plane immediately adjacent and of a radius equal to that of the wide toothed portion 22^a of the gear 22. The segment gear comprising the gear 24 and its sector 27 is caused, by the interposition 20 of the idler gear 23, to rotate in a direction opposite to that of the segment gear 22 but at the same peripheral speed.

A counter shaft 29 is mounted in the machine frame parallel to the shaft 18 and 30 carries a wide gear 30 and a pinion 31. The pinion 31 is constantly in mesh with a rack 32 downwardly facing from the bed 33. The gear 30 is arranged between planes which include the teeth 28 of the sector 27 35 and also the excess width of the teeth 22^a, but exclude the narrow teeth 22^b and the narrow teeth of the segment gear 24.

As the bed travels in one direction, the driving power is transmitted from the shaft 40 14 through the gears 15, 16, the transmission shaft 18, the gear 19, the segment gear 22, the gear teeth 22^a, the gear 30, the shaft 29, the pinion 31 and the rack 32; the driving of the bed in the opposite direction is 45 accomplished by power transmitted from the drive shaft 14 through the gear 15, the gear 16, the transmission shaft 18, the gear 20, the gear 23, the toothed sector 27 of the segment gear 24, the gear 30, the shaft 29, the pinion 31 and the rack 32.

The train of gearing from the drive shaft 14 up to and including the gear 22 with its segment of wide teeth 22^a on the one hand, and from the shaft 14 through the intermediate gearing to and including the toothed sector 28 on the other, rotate uniformly in one direction through the first set of gearing and in the other direction as to the second set. It follows that when the 50 gear 30 is in mesh with the teeth 22^a it rotates in one direction and while in mesh with the teeth 28 of the sector 27 it rotates in the opposite direction, whereby the bed is moved in one direction or the other 60 through the shaft 29, the pinion 31 and the 65

rack 32 according as the teeth 22^a or the teeth 28 have control of the gear 30.

As the teeth 22^a and the teeth 28 each occupy considerably less than one-half a circle, there is an interval of time when the gear 30 is not in mesh with either of the teeth 22^a or 28, at which time the gear 30, the shaft 29, the pinion 31 and the rack 32 are idle so far as any transmission of power is concerned. This interval of time occurs when the bed of the press is at or nearing the limit of its stroke in each direction. During this interval, the bed is under the control of the reversing mechanism which will now be described.

The crank arm 21 previously referred to as being fixed upon the end of the shaft 18 is connected by means of a wrist pin 34 to a link 35, the opposite end of which is pivoted at 36 to a reversing bar 37 guided within 70 bracket guides 38, 39 for rectilinear reciprocating motion above the shaft 14 and slightly below the plane of the bed 33. This reversing bar 37 is provided near its ends on the upper face with racks 40, 41 in 75 mesh respectively with loose pinions 42, 43 on stationary shafts 44 and 45 or, obviously, the pinions may be tight thereon and the shafts suitably journaled in the frame. The shafts 44, 45 have also mounted thereon pinions 46 and 47, the teeth of which extend into the horizontal plane of the rack 32 but to one side thereof. Intermediate the two ends of the bed 33 alongside the rack 32, in the vertical plane of the pinions 46, 47 is a 80 non-continuous or interrupted rack 48, 49, the rack portions of which are adapted to be engaged by the pinions 46, 47 immediately before, at the time of, and after the reversal of the direction of bed movement, the pinions 46 and 47 taking control of the bed 85 through the means of the short rack portions 48 and 49 immediately before the gear 30 leaves the teeth 22^a or 28, during the interval of time when the gear 30 is in mesh with either of the teeth 22^a or 28, and for a slight length of time after the gear 30 again engages the teeth 22^a or 28. The bed motion is thus during the period of reversal under the control of the reciprocating 90 bar 37, such control being received from the teeth 22^a and the teeth 28 of the regular bed drive at the exact speed of the bed movement between reversal points, without shock, the speed of the bed during the time that 95 it is controlled by the reversing bar 37 decreasing gradually from the full normal speed thereof to a standstill at the point of reversal and then gradually increasing until the speed of the bed drive is attained.

A noteworthy feature of the present invention is the fact that as the bed is slowing up under the control of the reversing bar, the said reversing bar is moving in a direction opposite to that of the bed, the 100

momentum of the latter serving to neutralize the jars of reversing and to counteract the effect on the press frame of the momentum of the bed as the latter is being slowed 5 down, in contradistinction to the usual form of device in which the reversing mechanism is moving at the time of reversal in the same direction as the bed, whereby the tendency to skid the press on the floor and the consequent strain on the frame is augmented. At 10 the instant of reversal, the bed being stationary, the reciprocating reversing bar 37 is also stationary, the crank arm 21 being at dead center. All of the advantages of the arcual motion of the crank are thus utilized, the 15 increase in motion of the reversing bar 37 being gradual from the dead center of the crank as it travels through an arc of 90° , at which time the bed is moving at its maximum speed and is then transferred to the 20 regular drive. It will also be observed that by the employment of the wide teeth 22^a extending over a segment of the gear 22, together with the coöperating sector 27, the 25 bed is driven alternately in opposite directions from the same drive shaft without the employment of gears shiftable upon their axes into and out of engagement with other gears. Moreover by the arrangement herein set forth, all of the bed reversing mechanism 30 is confined vertically to a space immediately below the bed whereby the lower space is utilizable for heavy pillars and other massive supports for the press, thus lending greater stability. It is to be noted 35 that if the reversing bar 37 were disposed below the center of gravity of the press, the movement of the reversing bar at the time of reversal counter to the direction of movement of the bed would by its momentum augment the momentum of the bed in the way 40 of a tendency to upset the press or subject the same to a torsional strain in a vertical plane about the center of gravity. The arrangement of the reversing bar immediately 45 below the bed and its movement counter to that of the bed at the time of reversal assists in neutralizing the strains during the reversing without a tendency to up-end the 50 press and with a less strain upon the frame than would otherwise be the case.

In Figs. 7, 8 and 9 is shown a simplified form of gear train for the driving of the bed in opposite direction during the medial portion of its stroke, the reversing mechanism 55 remaining the same as previously described. Herein the transmission of power from the drive shaft 14 through the gears 15 and 16 to the transmission or crank shaft 18 remains the same, power being further transmitted from the shaft 18 through the gear 19 to a substitute for the gear 22 which, in the present case instead of having wide and narrow teeth is a gear 61 mounted 60 upon the stub shaft 62 and having teeth

63 which may be of uniform width. Formed integral with the gear 61 or bolted thereto as indicated in fixed relation are two segment gears 64 and 65, the former lying immediately adjacent the gear 61 and the latter separated from the gear 61 by the width of the segment gear 64. The segment gear 64 extends through an arc of 120 degrees, as does also the segment gear 65, the two segments being angularly displaced so that the gap on one side of the shaft 62 embraces an arc of $30\frac{1}{2}$ degrees, while the gap on the other side embraces an arc of $89\frac{1}{2}$ degrees. Upon the countershaft 29 which carries the pinion 31 meshing with the bed rack 32 is mounted a pair of pinions 66 and 67, the former arranged to mesh with the segment gear 64. Alongside the shaft 29 is a stub shaft 68 carrying a wide or double faced pinion 69, one-half of the face of which is arranged to mesh with the segment gear 65 while the other half thereof is in mesh constantly with the pinion 67. The wide gear 69 runs idly upon the stub shaft 68 and serves for the reversal of the direction of rotation of the shaft 29 during the time the said pinion 69 is driven by the segment gear 65.

The operation of this gear train is as follows: The gear 61 and the segment gears 64 and 65 being constantly driven in the direction indicated by the arrows in Figs. 8 and 9, the segment gear 64 comes into mesh with the pinion 66 a sufficient length of time after the segment gear 65 has left the pinion 69 to permit of the reversal of the bed as previously described, by the reversing mechanism. The pinion 66 is driven by the segment gear 64 in a counter-clockwise direction thus moving the bed to the left through the mediation of the shaft 29 and pinion 31 meshing with the rack 32. After the teeth of the segment gear 64 clear those of the pinion 66, and allowing the same interval for the reversing of the direction of bed movement by the reversing mechanism, the teeth of the segment gear 65 come into mesh with the teeth of the pinion 69 rotating this pinion in a counter-clockwise direction and the movement of the pinion 69 being transmitted through the pinion 67 to the shaft 29 causing the latter to move in a clockwise direction and through the mediation of the pinion 31 and the rack 32 moving the bed to the right. During the functioning of the segment gear 65 the pinion 69 is thus used for driving the bed in a reverse direction, but during the functioning of the segment gear 64 the pinion 69 is running idle. It will be readily understood that the difference in the gap of $30\frac{1}{2}$ degrees and the gap of $89\frac{1}{2}$ degrees on the two sides of the shaft 62 is to compensate for the disposition of the pinions 66 and 67 on the one hand and the pinion 69 on the other in advance of each other, there

being a net interval of 60 degrees of arc between the functioning of the segment gears 64 and 65 to allow for the functioning of the reversing mechanism to slow down, stop and 5 accelerate the speed of the bed in the opposite direction.

It will be observed that in both forms of gear train, the driving, stopping and reversing of the bed motion is accomplished with 10 out the employment of axially shifted gears, in the first described construction by the employment of segment gears driven in opposite directions and in the form of construction last described by segment gears driven 15 in the same direction.

I claim:

1. The combination with a reciprocable bed, of means for driving the same and for reversing the movement thereof comprising 20 rotary driving means acting on the bed throughout the medial portion of each stroke, and reciprocating reversing mechanism for slowing down and reversing and accelerating the speed of the same at the 25 end of each stroke, said reversing mechanism including a bar moving when acting on the bed in a direction counter to that of the bed movement, said reciprocating reversing bar and bed disposed on the same side 30 of the center of gravity of the machine.

2. The combination with a reciprocable bed having one continuous rack and a second rack, of means for driving the same and for reversing the movement thereof comprising 35 rotary driving means acting on the continuous rack throughout the medial portion of each stroke, and reciprocating reversing mechanism for slowing down and reversing and accelerating the speed of the 40 same at the end of each stroke, said reversing mechanism comprising a revolving crank, a reversing bar mounted for reciprocatory movement and driven by the crank, a pair of pinions driven by the bar one at 45 each end and adapted to intermittently mesh with the respective portions of the second rack when the bed is near the end of its stroke.

3. The combination with a reciprocable 50 bed having a downwardly facing continuous rack, and a second downwardly facing rack, of means for driving the bed and for reversing the movement thereof comprising rotary driving means acting on the continuous 55 rack throughout the medial portion of each stroke, and reciprocating reversing mechanism for slowing down and reversing and accelerating the speed of the bed at the end of each stroke, said reversing mechanism

comprising a revolving crank, a reversing 60 bar mounted for reciprocatory movement below the bed and driven by the crank, a pair of pinions driven by the bar one at each end and adapted to intermittently mesh with the respective portions of the second rack 65 when the bed is near the end of its stroke.

4. The combination with a reciprocable bed having a downwardly facing continuous rack, and a second downwardly facing rack, of means for driving the bed and for 70 reversing the movement thereof comprising rotary driving means acting on the continuous rack throughout the medial portion of each stroke, and reciprocating reversing mechanism for slowing down and reversing 75 and accelerating the speed of the bed at the end of each stroke, said reversing mechanism comprising a revolving crank, a reversing bar mounted for reciprocatory movement below the bed and driven by the crank, 80 a pair of pinions driven by the bar one at each end and adapted to intermittently mesh with the respective portions of the second rack when the bed is near the end of its stroke said bar moving when in mesh with 85 the racks in a direction counter to that of the bed movement.

5. The combination with a reciprocable bed having a downwardly facing continuous rack, and a second downwardly facing 90 rack, of means for driving the bed and for reversing the movement thereof comprising rotary driving means acting on the continuous 95 rack throughout the medial portion of each stroke, and reciprocating reversing mechanism for slowing down and reversing and accelerating the speed of the bed at the end of each stroke, said reversing mechanism comprising a revolving crank, a reversing bar mounted for reciprocatory movement 100 below the bed and driven by the crank, a pair of pinions driven by the bar one at each end and adapted to intermittently mesh with the respective portions of the second rack when the bed is near the end of its 105 stroke, said bar moving when in mesh with the racks in a direction counter to that of the bed movement, the reciprocating reversing bar and bed disposed on the same side 110 of the center of gravity of the machine.

In witness whereof I have hereunto signed my name in the presence of two subscribing witnesses.

EDWARD FRANK DUDLEY.
